UNITED STATES PATENT OFFICE.

GEORGE M. WOLFF, OF MILWAUKEE, WISCONSIN.

BELT ELEVATOR.

1,167,869.

Specification of Letters Patent. Patented Jan. 11, 1916.

Application filed July 31, 1915. Serial No. 42,919.

To all whom it may concern:

Be it known that I, GEORGE M. WOLFF, a citizen of the United States, residing at Milwaukee, county of Milwaukee, and State 5 of Wisconsin, have invented new and useful Improvements in Belt Elevators, of which the following is a specification.

My invention relates to improvements in belt elevators of that type in which a series 10 of buckets are mounted upon an endless belt which travels around drums or pulleys at the top and bottom, the contents of the buckets being dumped when the bucket passes over the upper drum or pulley.

15 In elevators of the above mentioned type, the buckets are secured to the belt by riveting or bolting the back wall of each bucket to the belt along one or two transverse lines in close proximity to each other and usually 20 located at or near the transverse center line of the back wall of the bucket, whereby the belt is permitted to conform to the drums or pulleys over which it runs with minimum strain upon the bolts and the portions of the

25 belt and bucket engaged thereby. But it has been found that when elevators of this type are employed for elevating crushed stone or other hard materials having sharp or cutting edges, some of the fragments will 30 become lodged between the back wall of the bucket and the belt, (above the line of bolts), and will cut, tear and wear the belt adjacent to the bolts and thus greatly impair its strength and durability. In an effort to 35 overcome this difficulty, the line or lines of bolts have sometimes been located along the upper margins of the back wall of the bucket, but in such cases the weight of the bucket and the load contained therein im-

40 poses excessive strains when the belt passes over the upper drum or pulley and on the downwardly moving side the bucket tends to hang away from the belt and to exert vibratory strains upon the bolts. Such

45 buckets therefore tend to cut the belt and tear the bolts away from the belt or from the back wall of the bucket and for this reason it has been found more desirable to locate the bolts along the center of the back wall 50 as above stated, notwithstanding the cutting action exerted by fragments of material which become lodged between the back wall and the belt.

The object of my invention is to provide means to facilitate the discharge of fragments of material from between the back wall of the bucket and the belt, thereby adding to the strength and durability of the belt and also permitting the back wall of the bucket to conform to the surface of the belt throughout its length while traversing the space between the drums or pulleys.

In the drawings Figure 1 is a front elevation of a fragment of an elevator belt 65 showing a bucket embodying my invention attached thereto, the front wall of the bucket being partially broken away and one end wall of the bucket being shown in vertical section. Fig. 2 is a vertical sectional 70 view of the same drawn on line $x-x$ of Fig. 1. Fig. 3 is a view similar to Fig. 1, showing a modified form of construction so far as the features embodying my invention are concerned. Fig. 4 is a vertical sectional view of the same, drawn on line $y-y$ of Fig. 3.

Like parts are identified by the same reference characters throughout the several views.

The elevator belt A may be of any ordinary type. Each of the buckets is formed with a back wall B which is secured to the belt A, intermediate of its upper and lower margins and preferably adjacent to its 85 transverse center line, by one or more rows of bolts, C two rows of such bolts being illustrated. The front wall D of the bucket has its lower margin connected with the back wall and extends divergently upwardly 90 and outwardly, its side margins being connected with the side margins of the back wall by end walls E. The structure thus formed is substantially V-shape in cross section. The parts as thus far described 95 may be of any ordinary construction and the particular shape of the bucket is not essential. But it will be observed that the back wall B of my improved bucket is transversely slotted above the bolts, thereby 100 providing an opening F the length of which is nearly equal to the width of the bucket. The vertical dimensions of this slot F are nonessential, but the opening preferably extends from a line adjacent to the upper 105 line of bolts to another line near the upper

margin of the back wall B, leaving the end portions B' of the back wall connected by a comparatively narrow band B''.

In the construction shown in Figs. 1 and 5, the band B'' is reinforced by a flat bar or plate G which is secured to the band B'' by rivets g. A set of flat or substantially flat finger plates H have their upper ends interposed between the strips of metal G and 10 B'' and secured between these strips by the rivets g. These finger plates H are formed of resilient material and project downwardly across the slot F or substantially across the slot with their lower ends in close 15 proximity to the lower margin of the slot F, and adjacent to their lower extremities these finger plates are slightly bent or curved, as indicated at h, to provide a rounded surface for bearing contact with the belt A.

Any fragments of material which might otherwise become lodged between the belt A and the back wall B of the bucket above the bolts C, C, will, under light pressure, 25 cause the fingers H to spring inwardly, as indicated by dotted lines in Fig. 2, thereby relieving pressure upon the belt and preventing such fragments from cutting the belt. If not prevented by material within the bucket, these fragments will of course be 30 discharged from the space between the back wall of the bucket and the belt and drop into the bucket. I am thus enabled to secure all the advantages which might be obtained by 35 connecting the bucket to the belt along the upper margins of its back wall, and added thereto I secure the advantages of having the bucket connected to the belt along the transverse center of its back wall. In other 40 words, my improved bucket not only provides for the discharge of material which would otherwise lodge between the back wall and the belt, but it also provides a bucket which may pass with the belt around a pulley or drum with the load substantially balanced on the opposite sides of the line of bolts.

Referring now to Figs. 3 and 4, it will be 45 observed that the construction is substantially the same as that shown in Figs. 1 and 2, except in the following particulars. In the construction shown in Figs. 3 and 4, the resilient fingers H are omitted and the surface of the belt which would otherwise 50 be exposed through the slot F is covered by a flexible covering J fastened thereto and formed of any suitable material which can be easily replaced if damaged or worn and which is secured to the belt preferably at 55 top and bottom. It will also be observed that the slot F may be formed by suitably slitting the back wall B and folding the material upwardly and downwardly to form the reinforcing strips G' and K. The bolts 60 C' in this construction not only pass

through the back wall and belt, but they also pass through the reinforcing strip K which is integral with the back wall, since it comprises a portion of that wall which has been folded downwardly in forming the slot F.

In describing my invention with particularity, I do not wish to be understood as limiting the scope thereof to the specific form or forms of construction illustrated, the terms and expressions used being employed for the purpose of description and not of limitation.

I claim—

1. A bucket for belt elevators provided with a series of perforations near its transverse center line to facilitate connecting said bucket with a belt carrier, the back wall of said bucket above said line of perforations having a slot through which material may pass from the space in the rear of the upper portion of the back wall.

2. A bucket for belt elevators provided with a series of perforations near its transverse center line to facilitate connecting said bucket with a belt carrier, the back wall of said bucket above said line of perforations having a slot through which material may pass from the space in the rear of the upper portion of the back wall, and a flexible screen extending substantially across said slot.

3. A bucket for belt elevators provided with a series of perforations near its transverse center line to facilitate connecting said bucket with a belt carrier, the back wall of said bucket above said line of perforations having a slot through which material may pass from the space in the rear of the upper portion of the back wall, and a flexible screen extending substantially across said slot, said flexible screen comprising a series of resilient fingers composed of flat strips secured at their upper ends to the back wall of the bucket and projecting downwardly into the slot, substantially as described.

4. The combination with an elevator belt, of a bucket having the middle portion of its back wall secured to the belt and also having the upper portion of said wall apertured to allow material to pass through it from the space between such wall and the belt.

5. The combination with an elevator belt, of a bucket having the middle portion of its back wall secured to the belt and also having the upper portion of said wall apertured to allow material to pass through it from the space between such wall and the belt, and means for protecting the belt in the rear of said aperture from material contained in the bucket, said protecting means being adapted to permit material to enter the bucket from the space between the apertured wall and the belt.

6. A bucket for belt elevators provided

with means to facilitate connecting its back wall with a belt along a line intermediate of its upper and lower margins, and also having said back wall apertured above said line and in proximity thereto to permit material to pass into the bucket, from the space back of said wall.

In testimony whereof I affix my signature in the presence of two witnesses.

GEORGE M. WOLFF.
